F. L. DREEHOUSE,
PLOW DISK MOUNTING,
FILED JUNE 18, 1921.

UNITED STATES PATENT OFFICE.

FREDERICK L. DREEHOUSE, OF BARBER, IDAHO.

PLOW-DISK MOUNTING.

Application filed June 18, 1921. Serial No. 478,729.

To all whom it may concern:

Be it known that I, FREDERICK L. DREEHOUSE, a citizen of the United States, residing at Barber, in the county of Ada and 5 State of Idaho, have invented new and useful Improvements in Plow-Disk Mountings, of which the following is a specification.

This invention relates to disk plows and has for its object the provision of novel 10 means for mounting a plow disk upon the beam of a plow, the mounting including a casting rigidly secured to the plow beam and further including novel bearing means for the stem or shank which carries the disk.

15 An important object is the provision of a device of this character in which means is provided for preventing dust and dirt from coming in contact with the various bearings for the stem or shank of the disk.

20 An additional object is the provision of a mounting of this character which will be simple and inexpensive in manufacture and installation, highly efficient in use, durable in service and a general improvement in the 25 art.

With the above and other objects and advantages in view, the invention consists in the details of construction to be hereinafter more fully described, and claimed, and illustrated in the accompanying drawing, which 30 shows a cross sectional view through a plow beam and showing a disk associated therewith and including my novel mounting.

Referring more particularly to the drawing, the numeral 10 designates a field plow beam with which it is desired to associate a rotatable plow disk 11. In carrying out my invention I provide a casting 12 having a concaved base engaged against the convexed 40 side of the disk 11 and secured to the disk by means of suitable bolts 13. At its central portion this casting 12 is formed with an externally threaded extension 14 from which extends a reduced extension 15. The numeral 45 16 designates a shank or stem which passes through the casting 12 and which has a square head 17 fitting within a correspondingly shaped opening in the center of the disk 11. The free end of this shank or stem 50 16 is reduced as shown and is externally threaded, this free end being designated by the numeral 18.

The support for the stem or shank 16 comprises a casting 19 recessed at one side as indicated at 20 for conforming engagement 55 with the plow beam 10. This casting 19 is

disposed against one side of the beam against the other side of which is disposed a clamping plate 21 through which pass U-bolts 22 which entirely surround the casting 19 and which are provided with clamping nuts 23. At the end toward the disk the casting 19 is formed with an extension 24 which engages the reduced extension 15 of the casting 12. At its opposite end the casting 19 is formed with an externally threaded extension 25 for a purpose to be described. At its opposite side the casting 19 is formed with recesses 26 which communicate with a central bore 27 through which the stem or 70 shank 16 of the disk extends. Located within the recesses 26 are Timken bearings designated by the numeral 28 and disposed outwardly of the bearing members are thrust washers 29 against which are disposed roller 75 bearings 30 which are in turn engaged by other thrust washers 31.

Threaded upon the end 18 of the shank or stem 16 is a nut 32 of the castellated type which is held in proper position by means of 80 a cotter pin or the like 33 which passes through the nut and through the end 18 of the shank. Screwed upon the threaded extension 14 of the casting 12 is a dust cap 34 in which is disposed a felt washer 35 including a packing. Screwed upon the reduced extension 25 is a dust cap 36. Both of these dust caps are for the purpose of excluding dust and grit from the roller bearings, Timken bearings and thrust washers 90 which constitute the bearing means for the shaft or stem of the disk.

The casting 19 is preferably formed with a longitudinal duct which communicates with the bore 27 thereof and which has leading thereto a passage 38 into which is secured a grease cup 39 whereby to provide for proper lubrication.

From the foregoing description and a study of the drawings it will be apparent 100 that I have thus provided a simple and yet highly efficient mounting for a rotary disk of a plow whereby the disk will have the maximum amount of freedom of movement and the minimum frictional resistance, the 105 device being inexpensive and very simple and consequently not likely to get out of order.

While I have shown and described the preferred embodiment of the invention, it is of 110 course to be readily understood that I reserve the right to make such changes in the

form, construction and arrangement of the parts as will not depart from the spirit of the invention or the scope of the subjoined claim.

5 Having described the invention what I claim is:

Means for mounting a plow disk upon a plow beam, comprising a stub shaft carried by the disk and extending from the center 10 thereof, said shaft being formed at a point spaced from the disk with a tapered portion tapering toward the free end of the shaft, the intermediate portion of the shaft being of the same diameter as the smaller end of 15 said tapered portion, the shaft being formed with a second tapered portion near the end thereof and tapering toward the end, a member carried by the plow beam for receiving said shaft, said member being formed internally 20 at its side toward the disk with a tapered bearing surface opposite said first named tapered portion of the shaft, said

member being formed at its opposite side with a tapered bearing surface arranged opposite and tapered in the direction opposite to said second named tapered portion of the shaft, a bearing cone engaged upon the second named tapered portion of the shaft and having an outer surface opposite the second named tapered portion of the member 25 carried by the plow beam and tapered oppositely to the second named tapered portion of the shaft, means for retaining said bearing cone in position, a series of rollers engaged between the first named tapered portion of the shaft and the first named tapered portion of said member carried by a plow beam, and a second series of rollers engaged between said cone and the second named tapered portion of the member carried by the plow beam. 30 35 40

In testimony whereof I affix my signature.

FREDERICK L. DREEHOUSE.
